UNITED STATES PATENT OFFICE

GUSTAF DAVID SUNDSTRAND, OF ROCKFORD, ILLINOIS, ASSIGNOR, BY MESNE ASSIGNMENTS, TO SUNDSTRAND ENGINEERING COMPANY, OF ROCKFORD, ILLINOIS, A CORPORATION OF ILLINOIS

OIL BURNER AND CONTROL THEREFOR

Application filed April 14, 1924, Serial No. 706,240. Renewed May 22, 1929.

This invention has reference to a control for oil burners and more particularly to burners of the house-heating type.

Such burners ordinarily include oil-feeding means and air feeding means electrically driven, and an automatically functioning "regulator" or control device to set the oil-feeding means and the air-feeding means into operation according to conditions in the building or apartment to be heated. It is the object of the present invention to provide an improved system for such a burner which will automatically start and stop the device according to the room conditions and likewise according to the boiler conditions.

It is a particular object of the invention to provide reliable means operable to initiate combustion by adjustment or operation of the various parts in a predetermined sequence.

It is another object of the invention to provide a plurality of safety devices electrically associated for mutual co-operation to control the burner automatically by a change in both normal and abnormal conditions of the room or heater.

Another object of the invention is the provision of a novel ignition system employing a gas flame, electrically ignited, as the direct igniting means for the oil.

Still another object of the invention is the employment of a repeating mechanism adapted to cause a continued repetition of the starting operation in case of a failure thereof to ignite the oil, or upon extinguishing of the flame.

Still another object is the provision of improved means operated by the accumulated fuel to prevent operation of the device after numerous attempts at ignition caused by the operation of the repeating device.

A still further object of the invention is the provision of electrical circuits and of a construction adapted for the use of mercury switches to eliminate any danger which might arise from sparking at other types of switches.

Still other and ancillary objects and advantages will be apparent from the following description relating to one particular embodiment and application of my device.

The control proper is adaptable for use with various types of oil burners by making suitable and simple changes in the mechanical parts thereof. Furthermore, it is possible completely to separate the circuit of the electrical safety devices from the remaining part of the device, but this is usually not the preferable embodiment of the invention.

For the purpose of description and explanation I have chosen to illustrate in the drawings the invention as I have adapted and applied it to a type of oil-burning apparatus disclosed in my co-pending application Serial No. 575,642, filing date July 17, 1922. However, it is to be understood that this is by no means a limitation of the invention to such application, as will hereinafter be more apparent by the statement of the invention in the appended claims.

In the drawings: Figure 1 represents a steam boiler equipped with an oil burner comprising my control.

Fig. 2 is a front elevation of the oil drip switch for stopping the burner.

Fig. 3 is a vertical mid-section of the switch shown in Fig. 2.

Fig. 3a shows a combustion bowl which serves to collect unconsumed oil.

Fig. 4 is a front elevation of the controlling mechanism.

Fig. 5 is a plan view of the controlling mechanism from the plane of the line 5-5 in Fig. 4.

Fig. 6 is a diagrammatic view of the electric circuits of the control showing a low voltage circuit for the electrical safety switches.

Fig. 7 is a diagrammatic view of the electrical circuits for the control in which the safety devices are in circuit with the main power line.

Fig. 8 is a diagrammatic view representing the operation of cams in the controlling mechanism.

Fig. 9 is a side elevation of the mixture nozzle and the igniting means supported by the furnace door.

Fig. 10 is a plan view of the device shown in Fig. 9.

In the drawings the burner is shown ar-

ranged to heat a steam boiler 10. The oil burning apparatus supplies air, oil, gas for ignition of the oil and electricity for operating the apparatus and for igniting the gas. 5 The means for supplying these are associated into a unit supported on a box-like base 11 having a removable front plate 12. The controlling mechanism is situated within this base. Mounted on the base is an electric motor 14 aligned with an air blower 15 and connected to a suitable oil pump (not herein shown) likewise axially mounted with the motor and the blower. Electric current is suitably supplied through a main switch 16. 10 The air from the blower 15 is conducted through a large conduit 17 into the combustion space. Within the combustion space the air conduit 17 communicates with a suitable combustion bowl as 17a. A mixture of oil 15 and air produced by the motor-driven mechanism is supplied through a conduit 18 to a suitable nozzle 19 (Fig. 9) within the combustion space. The conduit passes through an opening (Fig. 9) in a plate 20 secured to 20 the door 21 of the boiler. Also secured to the plate 20 is a casing 22 for the ignition means. A tube 23 leads from a suitable gas supply to the control box. A gas tube 24 and an electric conduit 25 extend from the control box 25 to the casing 22. Portions of the conduits 18, 24 and 25 are of flexible construction so that the door 21 may be swung partially open when desired.

In the present embodiment of the invention, means is provided for heating an electrical resistance to incandescence, and then passing a stream of gas over the element to ignite the gas. The gas flame is projected into the path of the spray of oil and air 40 discharged from the nozzle 19 to ignite the oil, and air is supplied through the conduit 17 to continue the combustion, whereupon both the heating element and the gas are shut off. These operations are performed in 45 proper sequence by a controlling mechanism located in the box 11. Figs. 3 and 4 illustrate a particular embodiment of this mechanism in which rotary cams effect the sequential operation either through mechanical connections or through the operation of electrical switches.

The controlling mechanism comprises generally a rotary structure in the form of a shaft having a plurality of cams thereon, one 55 revolution of the shaft producing the starting and the stopping operations of the apparatus. The cams move certain arms one of which is adapted to cause the motion of the cams to be arrested in either of two positions, hereinafter referred to as the "idle" position and the "operating" position, such terms referring to the desired state of operation of the oil-burning apparatus. The mechanism generally is mounted in the box 60 11 by securing its base 30 therein. The ro-

tary shaft 31 has rigid thereon a plurality of cams 32, 33, 34, 35 and 36 and a gear 37. Means is provided to rotate the shaft comprising a small control motor 38 having a worm gear 39 on its shaft, suitably connected 70 to the gear 37 through a reducing gear train 40-41-42-43. An electrical connection board 44 is mounted on the base for simplifying the electrical connections to the various parts of the control. From this board a pair 75 of wires 45 lead to the control motor.

On a shaft 46 are mounted a plurality of arms which engage the corresponding cams. Each arm is suitably shaped for its distinctive operation, but each has a generally similar construction in certain respects. For example, each arm is individually demountable from the shaft 46 without regard to the others, whereby removal for inspection or repair is facilitated. Each arm is mounted for 80 assuming slightly angular positions on each side of the horizontal as illustrated by the two arms visible in Fig. 4. Each arm is provided with a roller 47 which rides on its cam. Arm 48 is shown with its roller in the depression of the cam, and arm 49 is shown with its roller on the raised portion of its cam. A short downwardly directed projection 50 is shown on arm 48 substantially at the pivotal center thereof, and a tension spring 51 is 85 attached thereto and to a stud 52. A slot in the arm directed angularly toward the spring provides at its circular bottom portion the pivotal bearing of the arm on the shaft 46, the arm being held immovable longitudinally 90 of the shaft by a peripheral groove 53 therein.

The arm 48 is provided with an extension to the right in Fig. 4 which is connected through a link 54 to a valve 55 in the oil supply pipe 55a leading to the intake side of the oil pump hereinbefore alluded to. The projection 50 above described is made longer than in the other cases to provide sufficient strength to operate the valve when the roller 47 rides into the depression of its cam 36.

The arm 49 has a similar extension to which a rod (not shown) may be attached to trip it manually independently of the cam 35. The arm 49 lies in a depression of its cam when the control is in both "idle" and "operating" positions. This is a necessary incident of the arrangement herein disclosed, since this arm 49 carries a mercury switch 56 provided with terminals 57, hereinafter called contact C, at the right end (Fig. 4) thereof. By this construction the contact is closed only when the roller on arm 49 rides on the elevations of its cam. This switch 56 is located on the circuit of the control motor 38 and is so disposed in the normal operation of the device that when the cams reach either the idle or the operating position, the circuit to the control motor is broken and the motion of the cams is arrested. The manual operation of the switch 100

56, independently of its cam, will set the control in operation for the purpose of testing or inspection without the necessity of disturbing the more delicate controls in the electrical control circuit.

5 The arm 58 which is operated by the cam 34, carries a mercury switch 59 having terminals 60 in the right end, hereinafter referred to as contact A, and terminals 61 in the left end, hereinafter referred to as contact B. This switch is tilted in one direction at the idle position of the cams and in the other direction at the operating position of the cams, functioning as a shifting means for 10 certain control circuits hereinafter described. It is arranged in the electrical circuits to permit starting of the control motor 38 by means other than through the above described switch 56.

20 The arm 62, which is operated by the cam 33, does not carry a switch, but is provided with a curved finger 63 (Fig. 4) which is pushed by the cam to open a spring-pressed gas valve 64 in the gas supply line 23. This 25 arm causes a flow of gas for a short period of time, depending upon the speed of the cams and the form of the cam 33.

The arm 66, which is operated by the cam 32, carries a mercury switch 67 having terminals 68, hereinafter called contact D, which are arranged in the circuit to the main motor 14, the cam 32 causing said circuit to be closed in the operating position of the cams.

30 Other arms, switches, and cams may be added as required. The addition of another cam and switch is desired in one particular application of my invention which is herein disclosed. This instance has reference to that form of the invention wherein the electrical control circuit is made independent of the circuits in the controlling mechanism, as will appear hereinafter. In Figs. 4 and 5 I have shown an ignition transformer having a primary coil 70 mounted on the control base

40 30. The primary terminals 71 are connected to the board 44. The secondary coil 72 of this transformer is a low-voltage heavy current carrying coil connected to an ignition element within the combustion space by the conductors 73 in the conduit 25. It may be desired to 45 close the primary circuit of the transformer by an independent switch so that it operates on passing from the idle to the operating position of the cams, during which interval ignition occurs. This is shown in Fig. 6 using cam 35^a of Fig. 8. However, it is preferably connected in parallel with the control motor 38 and is operated by the same mercury switch 56 by closure of contact C, as shown in 50 Fig. 7.

In the practical use of an oil burner it is started and stopped a number of times in every twenty-four hours. The success of such a burner is consequently greatly dependent 55 upon the reliability of the ignition means. I

have provided an ignition system which is practically isolated from the flame and hence not subject to disintegration or other deleterious effects arising from intense heat. In Figs. 9 and 10 the space at the right of the 70 door 21 is within the furnace or combustion space. Beneath the combustible mixture pipe 18 there passes through the door a casing 74, of tubular form provided on the inside of the furnace with a projecting spout or nozzle 75 75 opening into the furnace chamber and directed toward the jet of combustible mixture discharged from the nozzle 19. A gas flame issuing from the nozzle 75 ignites the combustible mixture.

The casing 74 contains a gas outlet 76 and an electrical resistance element 77 in the path of the gas from the outlet 76 to the nozzle 75. The gas line 24 is suitably connected to the outlet 76. The electrical conduit 25 enters the casing 22 and contains the wires 73 (Fig. 4) from the ignition transformer secondary coil 72. Rigidly mounted in the casing 74 and terminating within the casing 22 are two mutually insulated bus bars 79 and 80 to 80 which the wires 73 are secured by screws 81. Bolts 82 hold the bars together and insulation 83 spaces and insulates them. One of the bars 79 is mounted on a fixed plate 84 by a similar arrangement of bolts 85, and insulation 86. 85 The ignition element 77 is suitably connected to the bus bars 79 and 80.

In the operation of the above described ignition device, the casing 74 provides an ignition chamber containing the ignition element 77 and the gas orifice 76. Ignition takes place in the chamber thereby exhausting the oxygen therein, whereupon burning of the gas takes place from the tip of the spout 75. It is clear that in the operation of the oil burner, 105 the ignition element 77 is substantially removed from flames of both gas and oil at all times except at the initial ignition of the gas.

110 Means is provided for shutting off the whole apparatus by an accumulation of unconsumed oil. While such means generally are old the particular form employed is new and the operation of the same in relation to the mechanical and electrical controls is an 115 improvement over prior arrangements. The air blast conduit 17 (Figs. 1, 2 and 3) is connected to a combustion bowl 17^a within the furnace, said bowl being in the path of the combustible mixture sprayed from the nozzle 120 19. Unconsumed fuel will flow back into the air blast conduit 17 which is preferably slightly inclined for this purpose. A pipe 87 is connected to the air conduit to receive the draining oil. The pipe is provided with 125 an elbow 88 having a horizontally disposed axial nipple 89 upon which is mounted a rotatable hollow drum 90. Unconsumed oil may flow from the furnace into the drum through the above described connections. 130

The drum is provided with a normally vertical transverse partition 91 which passes to one side of the axial nipple 89, thereby permitting accumulation of oil in but one portion of the bottom of the drum. This unbalances the drum and tilts it on its axis. Mounted on the face of the drum is a casing 92 within which is disposed a mercury switch 93 having a contact at each end as G and 10 H with three wires 94, 95 and 96 leading thereto. The contact G is normally closed when the drum is empty and the contact H becomes closed when the drum tilts. A pouring spout 97 is provided for the purpose of 15 draining the oil from the drum by manually tilting it for that purpose.

In Fig. 1 there is shown in the boiler flue 10^a a thermostatic element 98 which is affected by the heat therein to move a mercury switch 99 to open its contact K. The function of this device is to cause repetition of the ignition operation in case of failure thereof or in case of extinguishment of the flames. The operation will be more specifically described hereinafter.

The sequence of operations, mechanically and electrically produced by the control mechanism above described, is diagrammatically represented by Fig. 8. This is arranged for 30 consideration in connection with Figs. 6 and 7 which represent diagrammatically the electrical circuits of the control. In the cam diagram (Fig. 8) the numbered lines represent the corresponding cams after being 35 rectified as to the cam surface. The rectification is indicated by the division of the circumference into 360°, these divisions being indicated in quadrant periods. With reference to cams 32, 35, 35^a and 36 in Fig. 8, the 40 shaded block above the lines indicates the elevations of the cam and likewise, in each case, the closure of the oil valve or switch contacts operated thereby. With reference to cams 33 and 34, the shaded block below 45 the line indicates the closure of the gas valve and contact B, respectively, when the roller lies in the depression of the cam. In the electrical diagrams those mercury switches which are operated by the cams have 50 contacts bearing designations by letter, already assigned above. In the cam diagram the same letter is placed in the shaded area to indicate directly that said contact is closed. In the case of the gas and oil valves the word 55 itself is inserted.

The complete operation of the device under normal conditions will be clear from the following description of Fig. 7. For the purpose of simplifying the explanation a 60 portion of Fig. 7 may be neglected so far as the normal operation is concerned. The wires 100, 101 and 102 are three wires leading from connection board 44 (Fig. 4) to a room thermostat 103 having the cold-side 65 contact E and the heat-side contact F. By

following the dotted lines 101^a and 102^a, the connection will be clearly understood, certain safety devices yet to be described being disregarded. The lines of the main current supply are indicated by the numerals 104 and 105. The main motor 14 is arranged to be connected in circuit across the power line through the mercury switch 67. The control motor 38 and the ignition transformer 70 are arranged to be connected mutually in parallel across the line, through the mercury switch 56. A variable resistance 106 may be employed in series with the control motor, as a suitable means for adjusting its speed for proper operation. The wires 107 and 108 form a shunt circuit around the contact C and lead to the room thermostat 103 through the cam tube contacts B and A in a well known manner.

Let us assume that the apparatus is in the idle position, the contact A being closed, as shown in Figs. 7 and 8. When the temperature in the room drops to the predetermined point, the room thermostat 103 closes the contact E, as shown in Fig. 7, thus completing the circuit (shown in heavy lines) to the control motor 38 through the following elements 104—108—102—E—100—A—107 thence through the motor 38 and the ignition transformer 70 to the line 105. The cams are caused to rotate out of the idle position to, say, one quarter turn or 90° in the diagram. The ignition element is heating up by the current from the transformer. The contact C has been closed so that the control motor 38 and the transformer 70 are acting independently of the room thermostat. The contact A has been opened, simultaneously with or after the closing of contact C so that there is no sparking at the break in the thermostat cam tube at contact A. The contact B is closed simultaneously with the opening of A so that the device is ready for closure of the hot side of the room thermostat. The shaft 31 continues to rotate. Shortly after the quarter turn the oil valve 55 is opened by the cam 36. At a half turn the gas valve 64 is opened and a circuit is closed through the main motor by cam 32 operating contact D. At 270°, or about a three-quarter turn, the gas valve 64 is closed. In the meantime the gas had been immediately ignited by the resistance element and the mixture of oil and air had reached the nozzle 19 and had been ignited by the gas flame before the gas was shut off. The burner now being in normal operating condition, the contact C is opened by cam 35 and the control motor 38 and the ignition transformer are thereby cut out and the mechanism stopped with the 110 cams resting in the operating position.

The contact B being closed by the shifting switch 59 the room thermostat must contact the hot side to again operate the control motor. When the room is sufficiently heated 115

the current is again established as before, but passes through wire 101 and contact B rather than wire 100 and contact A. As before, the cams turn and the control motor current 5 is transferred from the thermostat circuit to the cam tube contact C. Rotation of the cams immediately shuts off the oil, stops the main motor by opening contact D, and thereby places the apparatus in the idle position 10 where the contact C is broken and the control mechanism stops, ready for action again by closure of the cold side of the room thermostat.

Fig. 6 shows a modified form of electrical 15 circuit in which the room thermostat circuit including wires 107 and 108 is placed in a low voltage line rather than in the high voltage line of Fig. 7. This is accomplished by the use of two transformers having primary 20 coils 109 and 110 and low voltage secondary coils 111 and 112. The wires 107 and 108 are placed in circuit with the secondary coils 111 and 112 connected in series. One primary coil, as 109, is connected across the main 25 lines 104 and 105 by the wires 113 and 114. The remaining primary coil 110 is connected to one side of the line, as 105, by the wire 115 and to the motor side of the contact C by the wire 116. By this arrangement the coil 111 30 becomes the power source for the room thermostat circuit and the coil 112 becomes the load, inducing a current in the local circuit 110-116-38-105-115-110. The connections are necessarily so made that the coil 35 110 and the line voltage become opposed to each other, when the contact C is closed, to insure the proper operation of this arrangement. It will be observed that in Fig. 6 a separate cam tube contact C^a has been provided 40 for the ignition transformer and that a cam 35^a is indicated therefor in Fig. 8. This arrangement takes the ignition transformer from the circuit which is operated by the double transformer connection and 45 thereby permits use of transformers having a lower capacity than the arrangement of Fig. 7 would require, wherein the ignition transformer and the control motor are connected in parallel.

50 In Fig. 6 the parts are arranged in the operating position of the oil burner. This is indicated in the diagram by the heavy lines indicating current through the main motor 14. In this position the room thermostat must operate by closure of its heat contact F for which purpose the contact B is closed. The room thermostat is indicated 55 with the contact F still open, since the machine is operating to raise the room temperature sufficiently to close it. When this point is reached the low voltage circuit is completed, as follows: 111-112-108-94-G-96-M-102-F-101-B-107-111. The 60 current in this circuit induces a current in the local circuit 110-116-38-105-115-

110. The effect of this is to start the control motor 38 to bring the device from the operating to the idle position. Reference to Fig. 8 shows the sequence of operations. The control motor is put across the line voltage by 70 the cam 35 closing the contact C, the cam 34 opening the contact B simultaneously with or after closing C. The oil valve is shut by cam 36 and the main motor contact D broken by cam 32. The control motor rotates the 75 cams sufficiently to accomplish these operations, whereupon the cam 35 opens the contact C and the device stops in the idle position heretofore described with reference to Fig. 7.

80 A plurality of protective or safety devices are provided for the purpose of rendering the operation of the oil burner practically automatic in so far as it may be made to operate without human intervention.

85 From the above description it is apparent that the apparatus may be started or stopped by completing the circuit between wires 107 and 108. The effect of this has been generally described by considering the ordinary thermostat circuit having a heat side contact F and a cold side contact E (Fig. 7). The safety devices comprise a plurality of additional switches operatively associated with the boiler for actuation by conditions 90 therein, and effective to actuate the controlling mechanism exactly as conditions require. The ultimate effect is to close the circuit between wires 107 and 108 in each instance of operation.

95 First, means is provided to cause a repetition of the starting operation upon a failure to ignite. Said means is adapted to repeat the starting operation not only once, but indefinitely until ignition takes place or intervention occurs. The flue thermostat 98 heretofore alluded to is adapted when cold to close the contact K, thereby closing the heat circuit of the room thermostat by a shunt around the contact F. The thermostat 100 98 may be disposed anywhere near the combustion zone so as to be quickly heated upon initiation of fuel combustion.

105 Herein it has been described as located in the smoke flue. Upon response to the heat of the flue gases the thermostatic contact K opens. As shown in Fig. 7 the closure of K simulates a heated room, and hence stops the machine. No sooner is it stopped than the cold side of the room thermostat, (contact E) 110 restarts it and a new attempt is made to ignite the fuel. This will repeat indefinitely until ignition.

115 The repeating device is also operable as a recycling switch effective for this purpose 120 when the power is interrupted in the main line. If the power is so cut off, no part of the system can operate except the thermally operated members, these being the repeating switch 99, and the room thermostat 103. The 125 130

latter will generally be inoperative since it would be already closed at the cold side as evidenced by the fact that the burner is in running condition. Thus, the thermostatic switch 99 will cool off and close the contact K. When power in the line is again available the closure of contact K serves to move the control device to the idle position, whereupon the room thermostat immediately effects continuation of its operation to complete a cycle including the starting action. Thus, the repeating switch serves to recycle the starting mechanism on a failure in the power line whereby to produce ignition. It is a particular advantage of this recycling switch that it is not operative upon a momentary interruption of the power, but only upon such an interruption as is sufficient to extinguish the flame.

Secondly, I have provided the oil drip mechanism to limit recycling. The mercury switch 93 on the oil drip drum 90 has its contact G normally closed to complete the connection from wire 108 to wire 102 at the common point of the room thermostat by means of the following circuit, 108—94—G—96—M—102. Upon breaking contact G the room thermostat is cut out of the electrical control circuit. It is possible for the thermostat circuit to become broken while the main motor is running so that means must be provided to stop it. By using the contact H the immediate closure thereof short-circuits the leads 101 and 108 to the room heat contact F, by means of the wires 94, 95 and 117.

Thirdly, it is desirable that an excessive heat in the boiler or furnace 10 shall operate to stop the burner. This is accomplished in a well known manner by the use of a two point switch. In the steam boiler of Fig. 1, a pressure-controlled switch 118 has two contacts L and M (Fig. 7). Normally, the contact M is closed and completes the circuit from wire 96 to the room thermostat. At a predetermined maximum boiler pressure the contact M is snapped open and the contact L is closed. The opening of M cuts out the room thermostat so that it cannot operate to stop or start the burner. But the simultaneous closure of L short-circuits the leads to the heat circuit of the room thermostat by connecting wires 101 and 108 through the wires 117—118—contact L—wire 96—contact G—wire 94. Upon a drop in the boiler pressure to a predetermined low point the switch 118 is again shifted to snap closed the contact M for further normal operation of the device.

It will be understood that when the oil burner is applied to a hot water heating plant, a switch similar to the switch 118, but sensitive to the temperature of the water would be used.

By so connecting these various safety devices, each performs its functions at the

proper time and renders the burner idle or operative as the conditions require. No personal attention is required until the oil drip mechanism operates to cut out the whole of the electrical control in the idle position. Such operation only occurs when a radical fault exists requiring personal attention. Otherwise the control is automatic to a most efficient and desirable degree.

I claim as my invention:

1. A fuel burner for delivering fuel to a combustion space, comprising, in combination, means for supplying a mixture of oil and air to said space, means for supplying combustion supporting air to said space, a motor to operate said two supplying means, a supply of ignition fuel, an electrical ignition device, a valve to control the burner fuel, a valve to control the ignition fuel, a switch to control said motor, a switch to control said ignition device, a controlling mechanism for starting and stopping said burner automatically, a control motor for said mechanism, operatively effected by said ignition switch, a three-wire-two-circuit starting system for said control motor, shifting means to connect alternately one of said circuits across the ignition switch whereby to start the control motor upon closing said circuit, a plurality of cams in said controlling mechanism adapted to operate said fuel valves and motor switch to start and stop the burner, one of said cams operating said shifting means to connect the second controlling circuit across the ignition switch, another cam being adapted to operate the ignition switch to cut out the ignition device and to stop the control motor after a partial revolution of the cams, whereby the burner is left in operating condition, said ignition switch cam being likewise adapted to stop the control motor after a complete revolution of the cams, whereby the burner is left in idle position, the closure of the second controlling circuit starting said mechanism from the first stopped or operating position to the second stopped or idle position.

2. A fuel burner comprising, in combination, a heater, a heat absorbing medium therein to heat an apartment, a three-wire thermostat in said apartment, a motor for supplying combustion material to said heater, automatic ignition means to initiate combustion, an automatic self-stopping controlling mechanism arranged to start and stop said motor and ignition means, a starting circuit and a stopping circuit to said thermostat, means in said controlling mechanism for connecting said two circuits alternately to said controlling mechanism to effect the starting thereof by closure of the connected circuit, a two-way snap switch arranged to open one contact and to close another contact by a predetermined maximum state in the heater whereby to short the stopping circuit to the

- thermostat, said two-way snap switch being further arranged to open said second contact and to close said first contact at a predetermined minimum state in the heater whereby 5 to complete the circuits to the thermostat.
3. A fuel burner comprising, in combination, a heater, a heat absorbing medium therein to heat an apartment, a two-circuit thermostat in said apartment, a motor for supplying combustion material to said heater, automatic ignition means to initiate combustion, an automatic self-stopping controlling mechanism arranged to start and stop said motor and ignition means, a starting circuit 10 and a stopping circuit to said thermostat, means in said controlling mechanism for connecting said two circuits alternately to said controlling mechanism to effect the starting thereof by closure of the connected circuit, a double-contact switch arranged to have but one contact closed, one contact being normally closed and connected in each circuit to the thermostat, and the other contact being arranged when closed to short the stopping 15 circuit of the room thermostat, and means to operate said switch to short said circuit by an accumulation of unconsumed oil.
4. An oil burner for delivering fuel to a combustion space, having, in combination, means to supply combustion material to said space, a motor to operate said means, electrical means to ignite said material, a switch for said motor, a switch for said ignition means, a valve to control the supply of combustion material, a control motor, a switch for said control motor, a shunt circuit around said control motor switch, a two part control system for closing said shunt circuit to operate the control motor by operation 20 of one of said parts, shifting means to shift the control system for operation by the other part after closure of the control motor switch, a plurality of cams rotated by said control motor, said cams operating the above named elements, comprising, the motor switch, ignition switch, valve, shifting means, and the control motor switch, the latter being opened to stop the control motor with the cams in one position when set in motion by one part of the control system and in another position when set in motion by the other part of the control system, said positions determining the idle and operative condition of the oil burner.
5. An oil burner for a combustion space, having, in combination, means to supply fuel to said space, a motor to operate said means, a gas supply, electrical means to ignite the gas, a switch for said motor, a switch for said ignition means, a valve to control the supply of fuel, a valve to release the gas, a control motor, a switch for said control motor, a shunt circuit around said control motor switch, a two part control system for closing 25 said shunt circuit to operate the control motor by operation of one of said parts, shifting means to shift the control system for operation by the other part after closure of the control motor switch, a plurality of cams rotated by said control motor, said cams operating the above named elements, comprising, the motor switch, ignition switch, valve, shifting means, and the control motor switch, the latter being opened to stop the control motor with the cams in one position when set in motion by one part of the control system and in another position when set in motion by the other part of the control system, said positions determining the idle and operative condition of the oil burner.
6. A fuel burner comprising, in combination, a fuel burner, means for supplying fuel, means for supplying air thereto, a motor for said two means, a switch for the motor, an ignition fuel supply, electrical ignition means therefor, a valve for the burner fuel, a valve for the ignition fuel, a switch for said ignition means, a plurality of cams mounted for simultaneous rotation, a control motor for rotating said cams, a switch for said control motor, a shunt circuit around said switch, means in said circuit to start the control motor each of said switches and valves being operated by one of said cams, the control motor switch being closed at the beginning of the cam movement, and automatic means to break said shunt circuit when the control motor switch is closed, the revolution of said cams operating said valves and switches to stop and start the burner and to stop the control motor.
7. A fuel burner comprising, in combination, a fuel nozzle, means for supplying fuel thereto, a motor for said means, a switch for said motor, an ignition fuel supply, electrical ignition means therefor, a valve for the burner fuel, a valve for the ignition fuel, a switch for said ignition means, a control mechanism, a control motor for operating said mechanism, a switch for said control motor, alternative starting means for said control motor, said mechanism including means for operating the control motor switch, shifting means for the alternative starting means, means to operate the ignition switch, means to operate said fuel valve, means to operate said ignition fuel valve, said last five means operating after the operation of the first starting means, whereby combustion is established, the first of said five means being then operable to stop the mechanism, the other starting means being then operable to start the mechanism to operate said oil valve and the motor switch whereby to stop the burner, to shift the starting means and to open the control motor switch to stop the mechanism.
8. An oil burner apparatus having, in combination, with a heater having a furnace door, a bowl located in the heater, a conduit for

supplying air to the bowl, a fuel nozzle secured to the furnace door arranged to direct fuel down into the bowl, an ignition means arranged in the door to project a flame in the path of said fuel, flexible connections for said fuel and for said ignition means to permit the door to be opened, means to supply the fuel, means to supply air through the conduit, and controlling means to start and stop the burner according to heat requirements.

9. An oil burning apparatus having, in combination with a heater having a furnace door, a bowl in the heater, a conduit for supplying air to the bottom of the bowl, a fuel nozzle secured to the furnace door arranged to direct fuel into the bowl, an ignition means arranged in the door to project a gas flame in the path of said fuel, means to operate the ignition means, means to supply the fuel, means to supply air through the conduit, said conduit being arranged to drain oil from the bowl, controlling means to start and stop the burner according to heat requirements, said means including repeating means operable on failure of ignition to restart the controlling means, and means adapted to receive oil from the conduit on continued failure of combustion to render said burner idle and the controlling means inoperative.

10. An automatic safety device for an oil burner comprising, in combination, a burner, fuel supplying means therefor, ignition means therefor, means for automatically starting and stopping said burner, including operation of said ignition means, an electric control system for said automatic means, a repeating device in said system adapted to repeat the starting operation in case of failure of combustion, a device to collect unconsumed oil, a two-point switch in said system associated with said device, said device on accumulation of a predetermined quantity of oil being adapted to operate said switch, one side of said switch being arranged to open the circuit of the electric control and the other side of said switch being arranged to close the stopping circuit of the electric control inside the break in said circuit, whereby to render said control system ineffective and to stop said fuel feeding means.

11. The combination with a three-wire two-circuit apartment thermostat arranged to start and stop a fuel burner apparatus in a heater for said apartment by closure of the cold and hot side circuits of said thermostat, of a plurality of safety controls, comprising, a three-wire two-circuit heater control switch, a three-wire two-circuit cutout switch, a two-wire one-circuit repeating switch, each of said three-wire two-circuit switches having therein a wire common to both thermostat circuits, the common wire of the thermostat leading to one side of the heater control switch, the common wire of the heater control switch leading to one side of the cut out switch, the

common wire of the cut out switch and each side wire of the thermostat being the three wires leading to the apparatus, the other side of the heater control switch and the other side of the cut-out switch and one side of the repeating switch being connected to the heat side of the thermostat, and the other side of the repeating switch being connected to the common wire of the cut-out switch for operation substantially as described, said cut out switch and said control switch having at all times one circuit closed.

12. A thermostatic controlling device having, in combination, a device responsive to heat and cold, a circuit thereto closed by a predetermined degree of heat, another circuit thereto closed by a predetermined lower degree of heat, heat supplying means associated with the second circuit, said means being arranged to be started by closure of the second circuit, the closure of the first circuit stopping the heat supplying means, means arranged to make said circuits effective alternately in succession on said heat supplying means, and a switch across said first circuit open only during the period of heat supply, said switch otherwise closing said first circuit to stop the heat supplying means on failure thereof to supply heat.

13. In combination, an electrically operated burner, a control device to start and stop the burner in accordance with a demand for heat, one stopping and one starting operation constituting a cycle for said control device, means to actuate said control device whereby to stop and start the burner, a recycling switch arranged to be operated during the operating period of the burner by a failure of the power sufficient to extinguish the flame, said switch being further arranged so that, after operation by extinguishment of the flame and on return of power to the line, the switch actuates the control device to stop operation of the burner and to reposition the same for the starting operation by said actuating means, whereby the control device on failure of the power passes through a complete cycle.

14. In an oil burner, in combination, a main motor, a control motor, means including a room thermostat for initiating operation of the control motor, a plurality of cams rotated by the control motor, an oil supply valve arranged to be operated by one of said cams, a gas supply valve arranged to be operated by another of said cams, a switch controlling the control motor and arranged to be operated by another of said cams, and a switch controlling the main motor and arranged to be operated by another of said cams, the order of operations of the cams to start the oil burner being as follows: the closing of the control motor switch, the opening of the oil supply valve, the opening of the gas supply valve and the closing of the main

motor switch, the closing of the gas supply valve and the opening of the control motor switch.

15. A fuel burner comprising, in combination, a burner, a fuel supply valve, a motor for said burner, ignition means for said burner, a power operated controlling mechanism therefor embodying a rotating structure arranged to be moved intermittently and adapted during each revolution thereof to start and stop 10 said burner and independently operable devices actuated by said structure to control said motor, said fuel supply valve and said ignition means each independently of the other and all in operative sequence to start 15 the burner, and electrical means to actuate said mechanism comprising a motor for rotating said structure and automatic control mechanism operable to effect actuation of said structure between two predetermined 20 positions corresponding to the idle and operative conditions of the burner.

In testimony whereof, I have hereunto affixed my signature.

GUSTAF DAVID SUNDSTRAND.
